UNITED STATES PATENT OFFICE.

CHARLES WATSON MOBLEY, OF BARNESVILLE, GEORGIA.

DAILY-MILK-RECORD CABINET.

Application filed March 23, 1926. Serial No. 96,754.

One of the objects of my said invention is the provision of a daily milk record cabinet possessed of the practical advantages hereinafter ascribed to the same.

5 Another object of the invention is the provision of a combination milk record and medicine cabinet of peculiar and advantageous construction.

Another object is the provision of a cabinet 10 net which in addition to means for keeping the daily milk record of a number of cows, and this in a convenient and sanitary manner, is equipped with means for containing and preserving in a clean state a number of 15 record sheets for use in succession; the said means being so constructed and arranged as to lend itself to facility in removing a sheet and in placing the sheet in the cabinet for the reception of entries day by day.

20 Other objects and practical advantages of the invention will be fully understood from the following description and claims when the same are read in connection with the drawings, accompanying and forming part 25 of this specification, in which:

Figure 1 is a front elevation of the cabinet constituting the best practical embodiment of my invention of which I am cognizant.

30 Figure 2 is an enlarged fragmentary front elevation showing the upper portion of the front of the body of the cabinet as the same appears when the swingable, horizontally movable door is opened, and with 35 a portion of the magazine or container for record sheets partly in section.

Figure 3 is an enlarged transverse section taken through the roller of the cabinet and showing in edge elevation one of the clips, 40 four in number, on the said roller.

Figure 4 is a rear elevation of the cabinet.

Figure 5 is an enlarged vertical transverse section taken through the cabinet at an intermediate point in the length thereof.

45 Figure 6 is an enlarged fragmentary transverse section taken in the plane indicated by the line X—X of Figure 2, looking toward the left.

Similar numerals of reference designate 50 corresponding parts in all of the views of the drawings.

It is within the purview of my invention to form the different parts of my novel cabinet of materials best suited to the purposes of the parts, though I prefer to form 55 the roller 1 of wood, and the major portion

of the cabinet of galvanized sheet metal; and I also prefer to form the transparent panel 2 of clear glass, and to employ record sheets, in succession, the said sheets designated by 3 being of paper or other material consonant with the use to which the same are put. In this latter connection I would have it understood that a plurality of the sheets 3 is kept in the magazine 4, so as to protect the sheets against dirt and the action of the atmosphere, the sheets being removed one by one from the said magazine or container 4, and the magazine or container 4 being provided at its right hand end with a removable stopper 5, Figure 2, designed to lend itself to the ready removal of record sheets from the magazine or container 4 as occasion demands.

The major portion of my novel cabinet is 75 formed by a casing body 6 which is surrounded by the magazine or record sheet container 4, as illustrated. The said casing body 6 is closed at its back, bottom, top, and sides, but is open at its front, and by particular reference to Figures 5 and 6, it will be noted that the casing body 6 is provided at intervals in its height with shelves 7 whereby it is provided with a plurality of 80 compartments 8, designed more particularly 85 for the reception of medicine generally used for the protection of a herd of cows.

The uppermost shelf 7 is provided with an upturned lip 9, and in the compartment 8 above the said uppermost shelf 7 is arranged 90 the roller 1 before alluded to. The said roller 1 is provided with trunnions journaled in the side walls of the casing body 6, and one of the trunnions designated by 10 is equipped with a hand wheel 11 exterior of 95 the casing body, and also with a ratchet disk 12 disposed in the uppermost compartment, as clearly shown in Figure 6.

At 13 a resilient pawl is superimposed 100 upon and connected to the uppermost shelf 7, the said resilient pawl being designated by 14 and being provided by preference with a roller 15, arranged in opposed relation to the toothed periphery of the ratchet disk 12. Manifestly the use of the pawl 14 in association with the ratchet disk 12 is calculated to contribute to the facility with which the daily divisions 16 on the record sheet 3 may be registered with the narrow opening, hereinafter described, in the horizontal swingable door 17 of my improvement. The lower shelves 7 are provided 105 110

with upturned and preferably beaded flanges 18, and opposed to the said flanges 18 is what I designate the drop door 19 of my improvement, the said drop door 19 being hingedly connected at 20 to the casing body, Figure 6, and being adapted when closed to rest against the faces of the flanges 18 so as to effectively exclude the atmosphere from the interior of the several compartments 8. Manifestly to give access to any one or all of the several compartments 8 it is necessary to swing the drop door 19 forwardly, but this obviously may be readily accomplished after the door 17 is swung horizontally on its hinges 21 to open position. At 22 the door 17 is provided with an appropriate lock, preferably key controlled, and designed to cooperate with a keeper provided in the right hand side wall of the casing body 6. In addition to the narrow opening 16 and the lock 22, the door 17 is characterized by a platform or narrow shelf 23 and by end pockets 24, the said narrow shelf 23 being designed to support and the said pockets 24 being adapted to receive and hold the ends of the transparent panel 2, before mentioned, and a card 25 back of the said transparent panel; the said card 25 being provided with divisions bearing numbers, said numbers designating certain cows, and the spaces in the divisions and above the numbers being adapted for the reception of data germane to the particular cow represented by the number of the division. Manifestly the card 25 is adapted to be readily removed when necessary, and to be replaced with a fresh card intended to take care of any changes that may take place in the handling of a herd. For the attachment of the record sheet 3 to be used to the roller 1, I provide the said roller with a plurality of, preferably four, resilient clips 26, the said clips 26 being spaced apart, preferably in the relation shown in Figure 2, and being provided with barbs 27 adapted to extend through the upper portion of a record sheet and into the roller 1, so as to positively secure the record sheet to the roller. The clips 26 are capable of being sprung away from the roller 1, and from this it follows that by virtue of the clips 26 a record sheet may be expeditiously and easily attached to the roller 1, and may as readily be detached from said roller when filled with entries.

As designated by 28 and 29 in Figure 5, the horizontally swingable outer door 17 of the cabinet is provided with upper and lower flanges designed to rest above and below the casing body 6.

I prefer to employ my novel cabinet in upright position on a wall or other upright support, and toward said end I provide the casing body 6 with hanger loops 30, and 35 with a pendent apertured strap 31 through

the medium of which said casing body 6 may be attached to a wall or other upright support.

I illustrate in Figure 1 morning and afternoon divisions on the record sheet 3 in registration with the opening 16 in the door 17, and it will be noticed that each pair of divisions on the record sheet is in vertical alinement with one of the divisions of the card 25, so that the daily milk record of each cow may be expeditiously and easily entered upon the record sheet 3, and this with but little liability of the record sheet being soiled or otherwise affected by its exposure to the atmosphere through the opening 16. 80

In the practical use of my novel cabinet, it will be appreciated that the record sheet 3 is protected from prolonged exposure to light rays and hence the sheet is not liable to become discolored, and moreover the sheet is effectively protected against dirt, and milk and milk fat such as are likely to be upon a milker's hand. It will also be appreciated that at the end of a month or other predetermined period of time, the sheet filled with entries having to do with the daily milk weight from each cow, may be expeditiously and easily removed from the cabinet, so as to show clearly and cleanly the record of each cow for the month or other predetermined period. This will be appreciated as an important advantage when it is stated that the progressive dairy man is guided chiefly by the daily milk record of the cow. 95

In addition to the practical advantages ascribed to my novel cabinet, it will be noted that the cabinet is simple and inexpensive in construction, and in general is well adapted to withstand exposure at the point where it is located for convenient use of milkers 100 employed in connection with a herd.

I have entered into a detailed description of the construction and relative arrangement of the parts embraced in the present and preferred embodiment of my invention in order 110 to impart a full, clear and exact understanding of the said embodiment. I do not desire, however, to be understood as limiting myself to the construction and relative arrangement of parts as disclosed, my invention being defined by my appended claims within the scope of which modifications may be made without departing from my invention. 115

Having described my invention, what I 120 claim and desire to secure by Letters-Patent, is:—

1. A cabinet to keep an individual record of milk produced by the respective cows in a herd, comprising a casing open at its front, 125 a roller mounted in the upper portion of the casing and adapted to be turned about its axis to roll up thereon a vertically subdivided sheet on which a record is kept, a drop door hingedly connected at its upper end to 130

the upper portion of the casing body and over which the record sheet rests, and a front door hinged at one vertical edge thereof to the casing body and arranged when closed 5 to rest in front of the said record sheet the said front door being provided with pockets on either side and a shelf under the pockets to hold a card with a number for each cow, 10 the numbers being in line with the subdivisions of the record sheet, said front door also having an opening for the making of entries on the record sheet carried by the roller the sheet being arranged in pendant fashion 15 between the drop door and the front door and backed by said front door.

2. A cabinet comprising a casing open at its front with shelves therein, a drop door

hingedly connected at its upper end with the casing body and resting against the front of the shelves, a front door hinged at one 20 vertical edge thereof to the casing at one side of the drop door and having an opening below its upper edge and arranged when closed to rest in front of said drop door, and a roller above the top shelf for moving a 25 record sheet with vertical columns thereon between the drop door and said front door and past said opening in the front door, said front door having a card pocket above the opening therein to hold a card with numbers 30 to cooperate with the columns on the sheet.

In testimony whereof I affix my signature.

CHARLES WATSON MOBLEY.
